INVENTOR.

Harry W. Brown,
ATTORNEY.

UNITED STATES PATENT OFFICE.

MILTON ALDEN, OF SPRINGFIELD, MASSACHUSETTS.

VERNIER DIAL.

Application filed October 12, 1923. Serial No. 668,125.

To all whom it may concern:

Be it known that I, MILTON ALDEN, a citizen of the United States of America, residing at Springfield, county of Hampden, 5 Commonwealth of Massachusetts, have invented certain new and useful Improvements in Vernier Dials, of which the following is a specification.

This invention relates to improvements 10 in verniers and particularly to the adjustment of the graduated dial, whereby the tuning of a wireless set may be very accurately accomplished. At the present time the tuning adjustments are usually effected 15 by the operator rotating the dial by means of the knob and making these adjustments by observing the graduations on the dial with relation to the graduation on the fixed casing. This is unsatisfactory since the 20 average person cannot make these adjustments accurately or close enough in order to bring about a fine degree of tuning.

By means of my improvement the operator can effect a fine adjustment without any 25 very great care or attention on his part.

Broadly it comprises a gear attached to the graduated dial and a pinion cooperating therewith that may be readily moved so as to mesh with the gear or be withdrawn 30 therefrom. The diameters of the pinion and gear being such that fine adjustment of the tuning may be obtained for either the resistance or induction coils or the condenser plates. The device is so constructed and 35 arranged that the dial may be adjusted independently of the attachment.

Referring to the drawings:

Fig. 1 is a vertical sectional view through 40 the diameter of the dial and a portion of the casing showing the device attached to the dial.

Fig. 2 is a horizontal sectional view on the line 2—2 of Fig. 1 showing the gear and pinion out of mesh.

Fig. 3 is a detail view of the lever which is pivotally attached to the dial and on which the pinion is mounted, and

Fig. 4 is an elevational view of the attachment.

Referring to the drawings in detail:

1 designates a portion of the casing which encloses the wireless apparatus, 2 the vernier dial as a whole on which the usual graduations are placed. Attached to the dial is a 55 post 3 that fits into a socket 4 of the operating knob portion 5 and attached to the post

3 is a shaft 6 by means of the set screw 7 or other suitable device. This shaft passes loosely through the casing 1 and is attached to the inductance coil or to the movable condenser plates. 8 designates a plate a detail of which is shown in Fig. 3, that is formed with an opening 9 which fits loosely on the post 3. Attached to the plate 8 is the bolt 10 which is attached to the casing 1. 60 The other end of the plate 8 is formed with an elongated slot 11 in which is located the shaft 12 of the pinion 13. Attached to the shaft 12 of the pinion is an operating handle 14 which extends outward beyond the edge 70 of the dial, as shown to permit the operator to move the pinion 13 by means of the handle or post 15. Fixedly secured to the shaft 6 is a gear 16 by means of the pin 17 or other suitable means. It will be seen that 75 when the operator moves the handle 14 radially inward the pinion 13 is made to mesh with the gear 16, then by moving the handle 14 either upward or downward, as indicated by the arrows 18 in Fig. 2, the 80 dial 2 may be accurately adjusted and the condenser plates or the inductance or resistance coils adjusted for accurately tuning the instrument.

It will be noticed that when the pinion 85 13 is withdrawn from the gear 16 the dial 2 may be adjusted independently by the operator turning the knob 5. In operation the link or part 8 remains stationary on the post 3 and the gear 16 when operated by 90 the pinion 13 turns the gear 16 which rotates the dial 2.

From this description it will be seen that I have provided a very simple and inexpensive attachment for adjusting the dials of 95 verniers of a wireless set since the ratio of the diameters of the gear 16 to pinion 13 may be varied in order to increase the fineness of the adjustment. It enables any person to make a very fine adjustment or tuning 100 without carefully observing the graduations.

It will be observed that the part 14 extends outward beyond the edge 19 of the dial. It should also be observed that the handle 14 performs the dual purpose for 105 moving the pinion towards and from the gear 16 and for turning the pinion when in engagement with the gear 16 for adjusting the dial 2.

The instrument may be roughly tuned by 110 turning the dial by means of the knob part 5, then the final or accurate tuning is ac-

complished by moving the gear 13 into mesh with the gear 16 then, by operating the handle 14 the final tuning is accomplished which operates a resistance or inductance coil or the movable plates of a condenser. When the dial is turned by hand the post 3 revolves in the opening 9 of the plate 8, the gear 16, when the pinion 13 is out of mesh, turns with the dial 2.

10. What I claim is:

1. An operating device for adjustably rotating a vernier dial comprising in combination with the dial, a gear attached to the dial, a pinion, a shaft attached to the pinion, devices for moving the pinion into and out of mesh with the teeth of the gear which consists of a part having an elongated slot to receive the shaft of the pinion, and a part attached to the pinion for rotating the same and extending beyond the outer edge of the dial.

2. An adjusting device for a vernier dial having in combination with the dial, a post secured thereto, a gear attached to the post, a plate on the post which is attached to a fixed support and formed with an elongated opening, a pinion for engaging the gear, a shaft on the pinion and located in the opening, means attached to the shaft for moving the same in the opening for moving the pinion into and out of mesh with the gear, said means serving as a handle to rotate the pinion and dial.

3. An adjusting device for a vernier dial having a hub part and comprising in combination with the dial, a post attached to

the hub part, a shaft attached to the post, means attached to the post, and a part engaging said means for operating the same for adjusting the dial.

4. In a device for the purpose described, the combination with the hub of a dial, a recessed post attached thereto, an operating shaft attached to the post, a plate formed with an opening to receive the post and having one end attached to a fixed support and its other end formed with an elongated opening, a gear wheel attached to the post, a pinion for engaging the gear wheel, and means attached to the pinion which extends beyond the edge of the dial for operating the gear and turning the dial, said opening permitting the pinion to be moved into and out of mesh with the gear.

5. In a dial adjusting device the combination with the dial, a gear member attached to the dial, a pinion for engaging the gear member, means including a slotted plate, an operating handle connected to the plate and carrying the pinion for moving the pinion into and out of engagement with the gear member and for rotating the pinion and gear for adjusting the dial.

6. An operating device for a vernier dial comprising a gear attached to the dial, a slidably mounted pinion for engaging the gear, and means for rotating the pinion, said means including a shaft on the pinion, an arm attached to the shaft and a support for the pinion having an elongated opening to receive the shaft.

MILTON ALDEN.
